UNITED STATES PATENT OFFICE.

WILLIAM PEACOCK, OF LITITZ, PENNSYLVANIA, ASSIGNOR TO WOOLWORTH CHEMICAL COMPANY, OF LITITZ, PENNSYLVANIA, A CORPORATION OF PENNSYLVANIA.

CONTAINER FOR TABLE SILVER.

Application filed June 19, 1925. Serial No. 38,264.

To all whom it may concern:

Be it known that I, WILLIAM PEACOCK, a citizen of the United States, residing at Lititz, in the county of Lancaster and State 5 of Pennsylvania, have invented certain new and useful Improvements in Containers for Table Silver; and I do hereby declare the following to be a full, clear, and exact description of the invention, such as will enable others skilled in the art to which it 10 pertains to make and use the same.

This invention relates to containers for table silver and the like, and has for its object to provide a roll or container therefor 15 which is more efficient in use than those heretofore proposed.

With these and other objects in view, the invention resides in the novel details of construction and arrangement of parts as will 20 be more fully hereinafter disclosed and particularly pointed out in the claims.

Referring to the drawings, forming a part 25 of this specification, and in which like numerals designate like parts in all the views:—

Figure 1 is a plan view of a roll or container in full open position and with parts broken away to show the interior construction thereof;

Figure 2 is a plan view of the parts shown 30 in Fig. 1 after the first operation has been completed, of folding the container;

Figure 3 is a plan view of the parts shown 35 in Figs. 1 and 2, after the second fold of the closing operation;

Figure 4 is a plan view of the parts shown 40 in Fig. 3, and illustrating the next step in the operation of folding;

Figure 5 is a view similar to Fig. 4, showing a still further step in the folding operation;

Figure 6 is a plan view of the folded and tied roll;

Figure 7 is a fragmentary sectional view 45 taken as on the line 7—7 of Fig. 1, and looking in the direction of the arrows; and

Figure 8 is an enlarged detail sectional view illustrating the sealing of one of the compartments adapted to hold a piece of 50 silver.

This invention is drawn to those rolls or containers for silverware such as are in common use, which comprise a series of pockets into each of which is slipped one of the

pieces of table silver. It has been found 55 heretofore that silverware after being cleaned and polished, and then placed in one of the above mentioned rolls or containers and put away either in a showcase, buffet, or elsewhere, has not been prevented from tarnishing by the action of the sulphides in the air. That is to say, when a roll of silver has been taken out for use, it has been found necessary to clean and polish the silver, although said silver was cleaned and polished 60 before being put away in one of these containers. It is therefore to prevent the tarnishing of silver in such a roll as above described that this invention is directed.

The container or roll is composed of the 70 usual outer piece of colored flannel 1 and the inner piece of flannel 2 suitably stitched together around the edges as at 3. Between these two pieces of flannel, however, is inserted a sheet 4 of a pyroxyline nitrated cellulose sheet material, or other suitable 75 non-porous and pliable material adapted to prevent the passage of air therethrough.

Referring particularly to Fig. 1, another sheet of this pyroxyline material indicated 80 at 5, is placed through the central portion of the container and stitched, as at 6, and 7, to form the pockets 8 closed at one end and adapted to receive the pieces of silver, one of which is indicated as at 9. Tabs 10 are provided in this sheet 5 of pyroxyline material 85 and disposed at the open ends of the pockets 8 for a purpose that will presently appear. A suitable tape 12 is secured as at 13, to the sheet of flannel 1, for the purpose of tying 90 the rolled container. Suitable fastening devices, such as the well known snaps 15, are disposed as shown in the several views and secured to the sheet 1 of flannel.

Thus it will be seen from the foregoing, 95 that the silverware such as the spoons, indicated at 9, may be cleaned and polished, placed in the pockets 8, and the whole container may then be laid flat in an open condition, as shown in Fig. 1, in a jeweler's or 100 silversmith's showcase for the purpose of display. The pyroxyline material being transparent will show to good advantage the silver in the pockets formed therewith and thus the necessity of untying and opening a package of silver is obviated. In this instance, tarnishing of the silver in the showcase may be prevented in any suitable 105

way such for instance as by the use of a soda lime composition of matter, as disclosed in the United States Letters Patent No. 1,538,650, dated May 19, 1925, and applied for by William Peacock and Daniel Gray.

If it is not desired to leave the package of silver in the open position shown in Fig. 1, the container may be closed in the following 10 manner. The portion 20, see Figs. 1 and 2, may be folded upwardly and over the sheet of pyroxyline material 5, and then the opposite portion 22 of the container may be folded in a similar manner, thus forming 15 the package as seen in Fig. 3. The right hand portion 24 of the package may then be folded over to the left, as seen in Fig. 4, and the left hand portion 26 of the package may be folded over to the right to form the package 20 shown in Fig. 5. In this step of the folding operation, the snaps 15 will be utilized in the well known manner not necessary to describe, to secure the portions 24 and 26 in folded closed relation to the main 25 body portion of the package. The two halves 28 and 30 of the package shown in Fig. 5 are then brought together and the whole container then tied by the tape 12, producing the finished closed package 35 30 as seen in Fig. 6. To prevent the accidental turning over of the rounded corner portion 40, see Fig. 2, during the closing operation, there is provided a strip 41 of any suitable stiffening material such as whalebone, fiber stock, 35 paperoid, etc., secured to the container by the stitching 3. It will be noted that there are a plurality of these strips 41, which are so disposed as to prevent the corner 40 being folded or turned over in the closing operation, 40 thus providing an opening through which air may enter the container. In other words, it is desirous in this container to have no double thickness in any one layer of folded section, but on the other hand to insure 45 the portions such as 20 lying flat and smoothly over the pyroxyline sheet 5 when the same is folded as seen in Fig. 2, and likewise the portion 22 of the container by being provided with the strips 41 will always lie 50 smoothly when folded as seen in Fig. 3.

Referring to Figs. 1 and 8, it will be seen that when the portion 22 of the container is folded over onto the portion 20 to produce the package as seen in Fig. 3, the tabs 10 in 55 the sheet 5 of the pyroxyline will likewise be folded over and assume a position as seen in Fig. 8. That is to say, the tabs 10 will be folded as at 50, and will lie superimposed upon the sheet 5 as clearly shown in said 60 figure. Therefore, any air containing sulphides, etc., which might gain access to the closed container, and pass into the space 51, will be prevented from entering the pocket 8 in which is located a piece of silver 9. 65 Thus, the tabs 10 will serve as a seal to each

of the pockets 8. In securing the sheet 5 of pyroxyline material to the container, it may be stitched or secured in any other way suitable. If stitched, there may be provided strips 55 of material, as clearly shown in 70 Figs. 1 and 7, to prevent the stitching 7 from cutting the pyroxyline sheet 5.

From the foregoing, it will thus be seen that there is provided a container for table silver having an outer layer 1 of soft material with a layer 4 of non-porous material associated therewith. Also there is an inner layer 2 likewise of soft material having associated therewith a layer 5 of transparent non-porous material to provide a plurality 80 of pockets 8 for the pieces of silver. Further, this layer 5 has a plurality of projections or tabs 10 along one side, one tab to each pocket 8, so that when the container is folded each tab 10 will be folded back upon the main portion of the layer 5 so as to effectually close each open end of the pockets 8 to substantially make each of said pockets air-tight. That is to say, the portion 50 of each bent over tab 10 will form an effectual seal, preventing what little air is in the container from reaching the piece of silver in each pocket 8. The reinforcing strips 41 prevent a corner 40 of the container from bending over and thus forming a double fold of the corners whereby air may enter. Lastly, it will be seen that the snap fasteners 15 hold the container substantially in air-tight 90 folds by preventing the slippage of the middle portions of the flaps 20 and 22 on the inner turned over end portions 24 and 26 of 95 said flaps, and the tape 12 is adapted to secure the container in fastened folded position.

It is obvious that those skilled in the art may vary the details of construction as well as the arrangements of parts without departing from the spirit of the invention and therefore it is not desired to be limited to the exact disclosure above except as may be demanded by the claims.

What is claimed is:

1. In a container for table silver the combination of an outer layer; a layer of non-porous material associated therewith; an inner layer; a second layer of non-porous material associated with said inner layer to provide a plurality of pockets; means associated with said last named layer of non-porous material to make each pocket substantially air-tight; means to fasten said container in substantially air-tight folds; and means to secure said container in fastened folded position.

2. In a container for table silver the combination of an outer layer; a layer of non-porous material associated therewith; an inner layer; a second layer of transparent non-porous material associated with said inner layer to provide a plurality of pockets;

means associated with said last named layer of non-porous material to make each pocket substantially air-tight; means to fasten said container in substantially air-tight folds; 5 and means to secure said container in fastened folded position.

3. In a container for table silver the combination of an outer layer; a layer of non-porous material associated therewith; an inner layer; a second layer of transparent non-porous material associated with said inner layer to provide a plurality of pockets; means associated with said last named layer of non-porous material to make each pocket substantially air-tight; means comprising a 10 plurality of snaps to fasten said container in substantially air-tight folds; and means 15

to secure said container in fastened folded position.

4. In a container for table silver the combination of an outer layer; a layer of non-porous material associated therewith; an inner layer; a second layer of non-porous material associated with said inner layer to provide a plurality of pockets; means associated with said last named layer of non-porous material to make each pocket substantially air-tight; means associated with said outer layer to fasten said container in substantially air-tight folds; and means also 20 25 associated with said outer layer to secure said container in fastened folded position.

In testimony whereof I affix my signature.
WILLIAM PEACOCK.
